(57) **CLAIM**

The ornamental design for a mobile terminal with graphic user interface, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a mobile terminal with graphic user interface; and,

FIG. 2 is a front view of the mobile terminal with graphic user interface of FIG. 1.

The broken line drawing of a mobile terminal is for illustrative purpose only and forms no part of the claimed design.
